(57) **CLAIM**

The ornamental design for a marine engine, as shown and described.

DESCRIPTION

FIG. 1 is a perspective view of a marine engine showing our new design;

FIG. 2 is a top plan view thereof;

FIG. 3 is a front view thereof;

FIG. 4 is a right side view thereof;

FIG. 5 is a left side view thereof; and,

FIG. 6 is a rear view thereof.

The broken lines shown in the drawings are for the purpose of illustrating environment and form no part of the claimed design.
